UNITED STATES PATENT OFFICE.

PHILIP WUEST, JR., OF PHILADELPHIA, PENNSYLVANIA, ASSIGNOR TO
CHRISTOPHER J. HEPPE AND FLORENCE J. HEPPE, OF SAME PLACE.

DESIGN FOR A FRAME FOR ELECTRIC MOTORS.

SPECIFICATION forming part of Design No. 21,630, dated June 21, 1892.

Application filed May 12, 1892. Serial No. 432,791. Term of patent 14 years.

To all whom it may concern:

Be it known that I, PHILIP WUEST, Jr., a citizen of the United States, and a resident of Philadelphia, Pennsylvania, have invented 5 a new and original Design for an Electric Motor Frame, of which the following is a specification.

My design for the frame of an electric motor or dynamo is fully illustrated in the accompanying drawing, which represents the 10 frame in perspective.

AA are the two sides of the frame, circular in outline and having upwardly-extending portions BB, flat on top and having curved

inner surfaces bb. A cylindrical portion D 15 connects the two sides AA together. Extending from one side is a quadrangular flange D'.

I claim—

The design for the frame of a dynamo or 20 electric motor, as herein shown and described.

In testimony whereof I have signed my name to this specification in the presence of two subscribing witnesses.

PHILIP WUEST, JR.
